DOOR OPENING APPARATUS

William D. Ferris, Sterling, Ill., assignor to Frantz
Manufacturing Co., Sterling, Ill., a corporation
of Illinois

Application July 14, 1933, Serial No. 680,442

4 Claims. (Cl. 20—19)

This invention relates to garage doors in general, but more particularly to those that open into an overhead horizontal position.

Generally stated, the object of the invention is to provide a door that is operated by spring power, in combination with latching means for locking the door in closed position, and with means for electrically controlling said latching means from a more or less remote point of control, for causing the operation of the door by said spring power.

More specifically stated, it is also an object to provide an electrically controlled garage door of the kind that has an overhead horizontal open position.

It is also an object to provide certain details and features of construction tending to increase the general efficiency and desirability of an electrically controlled door of this particular character.

To the foregoing and other useful ends, the invention consists in matters hereinafter set forth and claimed, and shown in the accompanying drawings, in which—

Fig. 1 is a vertical section showing a garage door with controlling means embodying the principles of the invention.

Fig. 2 is an enlarged detail view of certain lever elements.

Fig. 3 is a similar view showing the parts in different positions.

Fig. 4 is an inside view of the door shown in Fig. 1 of the drawings.

Fig. 5 is an enlarged view of the latching mechanism shown in Fig. 4 of the drawings.

As thus illustrated, the door 1 has its upper corners provided with rollers 2 that travel on the parallel overhead tracks 3 inside the garage. The door is shown in vertical closed position in full lines, and at 4 in open position in dotted lines. Thus the door is rigid all over and has an overhead horizontal open position.

Levers 5, one at each side of the doorway, are pivoted at 6 on the tracks 1 and at 8 on the inner side of the lower portion of the door. Lifting springs 9, helical in form, are hitched at their lower ends to the building structure at 10, and at their upper ends to the upper ends of said lever at 11, adjustably, as shown. Said lever having rigid portions 12 to which are pivoted short links 13, and starting springs 14, helical in form, are fixed at their lower ends and connected at their upper ends to said short links. When the door is closed the springs and lever and links 55 are in the positions shown in Fig. 1, Fig. 2 and

Fig. 4 of the drawings. When the door is open, the said elements are in the position shown in Fig. 3 of the drawings. Thus the springs 14 are normally under tension to start the upward movement of the door, and the relatively heavy springs 9, also normally under tension, then raise the door into its open position.

It will be understood that such adjustment of the springs and such accuracy and relative arrangement of the parts is employed as will enable 10 the door to start tilting as soon as it is unlocked.

As the springs 14 are strong enough to start the door upward after it is unlocked, the invention contemplates more or less remote control by electric means to unlock the door, by any suitable 15 means. For example, latch bolts 15 and 16 are shown mounted on the door to project inside of the sides of the doorway when the door is closed. The bolt 15 is reciprocated by a lever 17, and the latter is connected by a wire or cable 18 with the 20 bolt 16, which latter has a coil spring 19 tending to keep both bolts in projected position. At one side of the doorway there is a reciprocating push rod 19, suitably mounted on the rear or inner side of the doorway, in line to operate the bolt 15 25 and, thereby, the bolt 16, to unlock the door. This rod 19 is operated by the armature 20 of the electromagnet 21 of any suitable character. When the magnet is energized, the two locking bolts are withdrawn and the door is moved into 30 open position by the spring power furnished by said springs. For the purpose of more or less remote control of said magnet, the energizing circuit thereof may have one or more push buttons 22 located in different positions, thereby to 35 conveniently open the door from the outside for a distance, or at the door. Inside, the hand lever 17 can be operated to unlock the door.

The ends of the bolts 15 and 16 may be beveled to strike the doorway and retract and allow the 40 door to move into the doorway when it is closed. The head 23 of the rod 19 holds the bolts in retracted position until the door is out a distance, when the door is opened.

Thus a spring operated door is locked in closed 45 position and the lock is electrically controlled to cause the automatic opening of the door into an overhead position. Although no means are shown specifically for electrically closing the door, it is obvious, however, that the invention, more 50 broadly considered, is not limited to the opening of the door.

With the arrangement shown and described, which is illustrative of the invention, there is nothing that projects into the doorway, upon 55

which anything might catch when the door is in overhead open position, and an automobile is safe against injury of that kind.

What I claim as my invention is:

- 5 1. In an automatic self-opening garage door of the class wherein springs are employed for opening the door, when the latter is unlocked, the combination of locking mechanism for attachment to the inner side of the door, and electromagnetic control mechanism forming no part of said locking mechanism and adapted and designed for attachment to the doorway in position to engage and move said locking mechanism into unlocking position on the door, thereby to unlock 10 the latter.
- 10 2. A structure as specified in claim 1, said locking mechanism comprising a pair of reciprocating locking bolts for opposite side edges of the door,

means including a pivoted hand lever forming a connection between the two bolts, and spring means for actuating one bolt into locking position, connected with said lever, thereby to actuate the other bolt into locking position, whereby both bolts are under the control of said electromagnetic mechanism.

3. A structure as specified in claim 1, said locking mechanism having spring means for moving this mechanism into locking position after the door is closed.

4. A structure as specified in claim 1, said electric control mechanism comprising an electromagnetic actuator which when energized serves to engage and move an element of said locking mechanism into unlocking position on the door.

WILLIAM D. FERRIS.
